UNITED STATES PATENT OFFICE.

JOHN H. KOONS, OF ANDERSON, INDIANA.

AIR-SHIELD.

No. 888,097.

Specification of Letters Patent.

Patented May 19, 1908.

Application filed June 24, 1907. Serial No. 380,469.

To all whom it may concern:

Be it known that I, JOHN H. KOONS, a citizen of the United States, residing at Anderson, in the county of Madison and State of Indiana, have invented a new and useful Air-Shield, of which the following is a specification.

My invention relates to a new and useful device for protecting workmen from the intense heat which streams out of the openings of certain types of furnaces, and the object of my improvement is to provide means whereby a curtain of rapidly moving air may be projected across the mouth of such an opening to prevent the heat therefrom from too greatly affecting the workmen.

My invention consists of a novel adjustable means to direct a wide, flat current of air across the opening of a furnace so that the heat issuing from such opening may be prevented from injuriously affecting persons whose duty it is to stand before it.

My invention is embodied in the construction illustrated in the accompanying drawings in which

Figure 1 is a view of a common type of gas heated furnace with my improved device secured thereto. Fig. 2 is a view of one form of my improved device. Fig. 3 is a cross section of the same parallel to the front of the furnace. Fig. 4 is a slightly modified construction of the same. Fig. 5 is a cross section of the device shown in Fig. 2 on the line 5—5. Fig. 6 is a cross section on the line 6—6 of Fig. 4.

Similar reference characters refer to like parts throughout the several views.

In the drawings 1 is a furnace provided with a hood 2 which projects outwardly over the space in front of the operating opening 3. The usual opening through the front wall near the top of the hood permits the heated air to pass from under the hood into the upper part of the furnace from which it escapes through the pipe 4. The air blast for this furnace is supplied by the pipe 5 which has a branch 6 which connects directly to my improved device through the connection 7.

My device consists of a body portion 8 which has upwardly projecting portions 9 and is adapted to be secured to the front of a furnace by means of lugs 10. This body is hollow and is provided with deflecting plates 11 and 12 to cause the air entering through the connection 7 to flow easily up and out through the side passages 13 and the long

horizontal passage 14. The plate 15 projecting forward from the body carries the gate 16 secured thereto by means of bolts 17, the slotted holes in the plate permitting the opening 18 to be any width desired. The side gates 19 are secured to the forwardly projecting bars 20, and by reason of slots in these plates 19, they may be set so that the openings 21 will be of any desired width. 60

Under ordinary conditions an intense heat streams out of the furnace through the opening 3, through which opening the workman introduces and withdraws the article to be heated, whether it be material for forging, 70 glass to be reheated or metal to be melted. The hands of the operator, even when protected by gloves, often become badly scorched and his clothing is very often ignited. When my improved device is 75 secured to the furnace, a current of cold air passes through the pipe 6 and the connection 7, out through the flat slot 18, up across in front of the opening 3 of the furnace, carrying up with it the extremely heated air at 80 the mouth of this opening 3, the blast being strong enough to remove the heated air as fast as it is heated. To prevent this blast or shield of air from becoming fan shaped and escaping into the work-room carrying 85 with it the heated air from the front of the opening 3, I provide means to prevent such lateral escapements. For this purpose the portions 9 of my device are provided with the openings 21 through which auxiliary 90 blasts press against the edges of the shield of air and prevent it from becoming fan shaped. The amount of blast will be regulated by the gates 16 and 19 according to the pressure of the air and the heat of the furnace. 95

Some furnaces receive liquid or gaseous fuel from the front, in which case I may provide the body of my improved apparatus with a passage 23 through which the fuel may be conducted into the furnace. It may also be necessary to connect for the blast of air at the front of the body as shown in Fig. 2 where an opening for the pipe 25 is formed in the front of the body 24. 100

In Figs. 3 and 5 is shown a plug 26 screwed into a threaded opening into the bottom of the body portion so that in case any undesirable substance such as drips of glass and metallic scale and slag should fall through 110 the opening 18 it may be withdrawn through the opening in the bottom.

While my improved device is illustrated as a box with upwardly projecting portions 9, circumstances may direct variations to fit different conditions, and these changes may be readily made by furnace designers.

Having now explained my invention, what I claim as my invention and desire to secure by Letters Patent is,—

1. A hollow device adapted to be connected to an air pipe, and to be secured adjacent to an opening into a highly heated space, and having a longitudinal slot, and a horizontally movable gate for controlling the width of the slot.

15 2. A hollow box adapted to be secured to

the front of a furnace and provided with a connection to an air pipe, upwardly extending portions formed on said box, said box having a longitudinal slot, and said auxiliary portions having vertical slots, and gates 20 whereby the width of said slots may be varied.

In testimony whereof I have signed this specification in the presence of two subscribing witnesses.

JOHN H. KOONS.
